UNITED STATES PATENT OFFICE.

ARVID PETERSON, OF TRENTON, NEW JERSEY, ASSIGNOR TO DE LAVAL STEAM TURBINE COMPANY, OF TRENTON, NEW JERSEY, A CORPORATION OF NEW JERSEY.

WATER TURBINE.

Application filed July 29, 1922. Serial No. 578,298.

To all whom it may concern:

Be it known that I, ARVID PETERSON, a citizen of the United States, residing at Trenton, county of Mercer, and State of

5 New Jersey, have invented a new and useful Improvement in Water Turbines, of which the following is a full, clear, and exact description, reference being had to the accompanying drawings, which form a part of this

10 specification.

My invention relates to an improvement in water turbines whereby the standard pump may be readily converted into a turbine.

A water turbine, for example, differs from 15 a centrifugal pump substantially only in the fact that in the former the water gives up energy to a wheel, while in the latter energy is supplied to the water by a wheel.

The demand for small turbines is 20 comparatively limited and as a result at present their cost is comparatively high, while on the other hand centrifugal pumps of small size, say up to 18-20 inches, are made up on a manufacturing basis in quantities and 25 their cost is relatively reasonable.

Now the object of my invention is to so construct a water turbine that relatively inexpensive centrifugal pump parts may be used for making up the water turbine.

30 Having now indicated in a general way the nature, purpose and advantage of my invention, I will proceed to describe a preferred embodiment thereof with reference to the accompanying drawings, in which:—

35 Fig. 1 is a sectional view in the plane of flow of fluid pressure of a water turbine constructed from centrifugal pump parts in accordance with my invention.

Fig. 2 is a view, partly in section, of the 40 subject of Fig. 1 at right angles.

Fig. 3 is a partial section, similar to Fig. 2, showing the original pump parts in the casing.

The parts shown in the drawings are those 45 of a water turbine comprising a casing *a*, provided with a cover *b*, and through which passes a shaft *c*, carried in suitable bearings. The casing is provided with the usual inlet and discharge passages *e* and *f*, respectively.

50 Circular grooves *g*, *g* are provided in the casing into which fit diffusing rings *h*, *h* to which are attached guide vanes *i* which serve to concentrate and direct the motive fluid into the turbine wheel *j*, suitably mounted

55 on shaft *c*.

The side plates of the turbine wheel are fitted with wearing rings *l*, *l* which rotate on the inside of the ends of diffusing rings *h*, *h*.

In converting the standard pump, shown 60 for comparison in Fig. 3, into a turbine, it is only necessary to remove the standard stationary impeller wearing rings *x*, *x* from the circular grooves *g*, *g*, in which they ordinarily fit, and insert the diffusing rings 65 *h*, *h*, to which guide vanes *i* are attached. The substitution of a turbine wheel *j* for the standard pump impeller *y* completes the conversion, the parts of the standard pump remaining otherwise the same in the turbine. 70

Having now fully described my invention, what I claim and desire to protect by Letters Patent is:

1. As an article of manufacture, a casing 75 adapted to support interchangeably a stationary impeller ring or a diffusing ring adapted for cooperation with a turbine wheel.

2. As an article of manufacture, a casing 80 adapted to support a stationary impeller ring or fixedly a diffusing ring adapted for cooperation with a turbine wheel.

3. As an article of manufacture, in combination, a casing provided with an annular 85 recess adapted for the reception of a stationary impeller ring and a diffusing ring, adapted to cooperate with a turbine wheel, provided with means adapted to enter said recess. 90

4. As an article of manufacture, in combination, a casing provided with an annular recess adapted for cooperation with a stationary impeller ring and a diffusing ring provided with a flange adapted to enter said 95 recess whereby said ring is supported in operative relation to a turbine wheel.

5. As an article of manufacture, in combination, a casing provided with spaced annular grooves adapted to cooperate with stationary impeller rings and diffusing rings 100 engaging in said grooves, said rings supporting vanes which form nozzles adapted to direct fluid to a turbine wheel.

In testimony of which invention, I have 105 hereunto set my hand, at Trenton, on this 27th day of July, 1922.

ARVID PETERSON.
